UNITED STATES PATENT OFFICE.

JOHN C. KOPF, OF BELLEVUE BOROUGH, PENNSYLVANIA, ASSIGNOR TO THE DUFF MANUFACTURING COMPANY, OF PITTSBURGH, PENNSYLVANIA, A CORPORATION OF PENNSYLVANIA.

LIFTING-JACK.

1,397,870.

Specification of Letters Patent.

Patented Nov. 22, 1921.

Application filed February 4, 1921. Serial No. 442,368.

To all whom it may concern:

Be it known that I, JOHN C. KOPF, a citizen of the United States, and a resident of the borough of Bellevue, in the county of 5 Allegheny and State of Pennsylvania, have invented a new and useful Lifting-Jack, of which the following is a specification.

This invention relates to lifting jacks of the kind that is operated through a worm 10 and worm-wheel rotating a pinion meshing with rack-teeth on the lifting-bar, the worm and worm-wheel being of steep-pitch so as to reduce the end-thrust resistance to manual operation, and consequently requiring to be 15 held in order to sustain the load; the holding means being ordinarily a constantly applied brake. In a prior application, Serial No. 405,401, filed August 23, 1920, I have disclosed an improved jack of this type, having in its combination a holding device 20 which utilizes this end-thrust of the lifting worm, and which is therefore, necessarily reliable and also permits of easier operation since its resistance to lifting and lowering 25 by the operator is only what the load requires to sustain it. According to the present invention a jack thus constructed which is lifted manually by power applied to the worm-shaft overcoming the friction of the 30 holding device, is lowered automatically by controllably relieving the thrust pressure, and thereby the friction, in the device, so that the loaded rack-bar comes down by itself.

35 In the accompanying drawings, forming a part hereof:

Figure 1 is an elevation of the jack, looking at the interior with the cover-plate removed;

40 Fig. 2 is a sectional elevation looking at right angles to Fig. 1; and

Fig. 3 is a horizontal section in the plane of the section of the operating shaft, which, with the lowering device is seen in plan elevation.

The jack has a stand frame 1, in which a jack-bar or jacking member 2, provided with rack teeth 3 on one side, is vertically guided.

The rack teeth are meshed by a pinion 4 50 cut on a shaft 5, which is journaled in front and rear bearings 6 and 7 in a gear case 8, the bearing 6 being removable to permit the insertion of the pinion into its rear chamber 9. On the forward part of the 55 pinion shaft, in a front or outer chamber

10 of the gear case, rendered accessible by a cover 11, is a worm-wheel 12, larger than the pinion.

An operating shaft 13 is arranged transversely below the axis of the pinion and 60 worm, in bearings half in the body of the frame and half in the cover 11; and on this shaft within the chamber 10 is a worm 14 meshing the worm-wheel. A lever rocker or ratchet case 15, socketed for the reception 65 of a handle-bar and containing a double reversible pawl 29, is mounted to oscillate on the outwardly projecting portion of this shaft, in coöperation with a ratchet wheel 16 fixed on a hexagonal seat 17. By means of 70 this ratchet lever the load is lifted.

When load is on the rack-bar, whether at rest, or when lifting or lowering, the action of the load is transmitted and reduced through the gearing and applied to the 75 worm, where because of the pitch its effect is partly to rotate the worm 14 and partly to press it endwise, creating a constant moderate end-thrust pressure, toward the right in Fig. 1. Between this end of the worm and 80 the frame there are introduced, in accordance with my prior invention two disks 18 and 19 having flat smooth surfaces to co-operate with each other and with similar surfaces 20 and 21 formed on the end of the 85 worm and the interior of the frame. The disk 18 has a round central opening encircling the shaft, and an external notch 23 which engages an anchoring rib 24 projecting from the rear wall of the chamber 10 90 of the frame. This disk is thus held against rotation, while free to be pressed axially against the disk 19. The latter disk is engaged to rotate with the shaft, while also free axially, by means of lateral notches 25 95 in its interior opening and a cross-pin 27 in the shaft, the ends of which project into the notches. There are thus three friction surfaces which are rotatable with the shaft and worm, and three opposed surfaces which are 100 stationary in respect to rotation, the alternating fixed and rotatable elements being adapted to be compacted by the end-thrust against the abutment support of the frame. Through the friction thus produced, the 105 load is securely held by its own action against running down, the holding being proportional to the load; so that the lighter the load the less the resistance. Therefore, the friction, while always sufficient to hold 110

the load, is easily overcome by the handle leverage upon the operating shaft in lifting and lowering.

Additional pressure of small amount is provided by a light spring 28 encircling the shaft between the other end of the worm and the remote wall of the chamber. This spring serves to prevent the ratchet wheel 16 being dragged back by the spring-pressed pawl 29 on the upstrokes of the lever, when the jack-bar is being raised to the load.

The parts described so far are present in my prior application aforesaid. I now include a device which further reduces the labor in the operation of the jack, while preserving the feature of safety, by rendering the lowering automatic. To this end a screw 30 having a rounded end 31 to bear upon the end of the operating shaft is located in an internally screw-threaded socket 32 at the end of the shaft remote from the ratchet lever. This screw is provided with a hand-wheel 33, by means of which the screw can be readily and exactly moved in and out. The end of the shaft is caused to project into the back or inner end of this socket, so that when the screw is advanced slightly it pushes back on the shaft against the end-thrust pressure derived from the load. This relieves the pressure, and consequently the friction, between the surfaces of the holding device, and thereby permits the shaft to rotate under the action of the load, which sinks with the rack-bar. As the friction sur-

faces are flat and smooth and the slight end movement is delicately adjustable by the screw, the descent can be very nicely controlled. When lowering in this manner, the handle-bar is of course removed from the socket 15, and the latter may revolve with the shaft.

What I claim as new is:

1. In a jack, the combination with a frame, a rack-bar, a pinion meshing with the rack-bar, a worm-wheel on the axis of the pinion, an operating shaft, and a worm on the operating shaft meshing the worm-wheel, said worm and worm-wheel of steep pitch, of means for actuating said worm shaft to lift the load, a friction-holding device actuated by the end-thrust of the worm, and means for relieving the end-thrust pressure in said holding device to let the rack-bar run down by gravity.

2. In a jack, the combination with a frame, a rack-bar, a pinion meshing with the rack-bar, a worm-wheel on the axis of the pinion, an operating shaft, and a worm on the operating shaft meshing the worm-wheel, said worm and worm-wheel of steep pitch, of a ratchet-lever lifting device on one end of said shaft, friction holding disks interposed between the worm and the frame, and a lowering device adapted to act upon the end of the shaft remote from the ratchet-lever device in opposition to the end-thrust on said disks.

JOHN C. KOPF.
